Albert L. Sipe

UNITED STATES PATENT OFFICE.

ALBERT L. SIPE, OF CARDINGTON, OHIO.

WAGON-RACK.

SPECIFICATION forming part of Letters Patent No. 654,767, dated July 31, 1900.

Application filed April 12, 1900. Serial No. 12,657. (No model.)

To all whom it may concern:

Be it known that I, ALBERT L. SIPE, a citizen of the United States, residing at Cardington, in the county of Morrow and State of Ohio, 5 have invented certain new and useful Improvements in Wagon-Racks; and I do hereby declare the following to be a full, clear, and exact description of the invention, such as will enable others skilled in the art to which it appertains to make and use the same.

The object of my invention is the production of a wagon-rack the main body of which may be used separate from the rack for hauling stone, brick, logs, &c., or any like heavy 15 loads and the rack of which when adjusted to the said main body in a closed condition may be used for hauling hogs, sheep, wood, corn, &c., and when the sides of the rack are extended at an angle to the sides of the main 20 body the same can be used as a hay-rack.

Figure 1 is a side elevation of my wagon-rack. Fig. 2 is an end view of the rear end-gate, partly in section; and Fig. 3 is an inner end view of the front gate. Fig. 4 is a transverse section showing the rack open and adjusted as a hay-rack:

On the accompanying drawings, 1 represents the main body portion of the wagon-rack, having under cross-sills 2, supported 30 by strips 3, of any suitable material, bent in **U** shape and passing beneath the said sills and fastened to the side of the main body. The said sills 2 are further supported by stays or braces 4, which are formed **U** shape in 35 cross-section and flattened at their ends to receive fastening means, the lower end of each of said braces being formed with an aperture. The sills 2 extend beyond the sides of the main body in order to receive the braces 40 and are beveled at the ends, and each is provided with an aperture to register with the aperture in the end of each brace 4 to receive supporting-rods, as will be hereinafter described.

45 The sides of the main body carry hooks 5 for engaging eyes 6. The front end-gate also carries similar hooks for same purpose, and both the front and rear end-gates carry pairs of loops 7 for receiving standards 8 50 of the top gates. An important feature of the front end-gate is the fact that it carries hooks 9 on the inside of same, which hooks

are adapted to engage and hold by tension the hooked rods 10.

The top front and rear end-gates are composed of strips of material fastened together and held in place by the standards 8, which posts are adapted to be dropped into the loops 7, as before described. Each top gate also carries a pair of half-loops 11, which in conjunction with the posts 8 form eyes or guides, which receive uprights 12, the uprights on the front gate being connected at the top by a chain. The top front end-gate carries hooks 13, one on each end of the top strip thereof, for engaging the hook of the hooked rod 10 when the sides of the frame are extended at an angle to the sides of the main body and to support the said rods when held on a tension by the hooks 9. The top 70 sides 17 are also composed of strips of material fastened together and held in place by standards 14, each of the said standards having a slot cut in the lower end and carrying an eye at the lower end thereof for engaging 75 hook 5, said eye comprising a **U**-shaped piece fastened in any suitable manner to the said standard.

The upper end of each of the standards 14 carries a brace-rod 15, which is pivoted at its 80 upper end to the said standard, preferably by a bolt passing through an eye in the said brace-rod, said bolt being carried by ears 16 of any suitable material. The brace-rod 15 is also provided near its lower end with a 85 shoulder which is adapted to rest upon the edge of the aperture in each end of each sill 2 when the sides of rack are extended at an angle to the sides of the main body.

Suitable chains 18 are provided for retaining the top sides 17 of the upper frame in a closed condition; but said chains may be unhooked at their middle when it is desired to drop the sides at an angle. One of the hooked rods 10 is carried by the upper strip of each 95 of the top sides 17 by means of ears 19. (See Fig. 3.) The hook portion of the rod 10 is adapted to engage the hook 13 when the top sides are extended at an angle to the wagon and to pass beneath the hook 13, so that the 100 rod will be held on a tension between the hook 13 and hook 9.

In practice my invention may be used for hauling heavy loads by simply removing the

top sides and top end-gates for sheep, hogs, wood, corn, &c., by adjusting the top end-gates and sides in a closed position, and as a hay-rack by extending the top sides at an angle to the sides of the main body. To adjust the top sides and top end-gates in a closed condition, it is only necessary to drop the standards 8 of the front and rear top end-gates into the loops 7, engage the hooks 5 on the sides of the main body by the eyes 6 of the top sides, hook the two halves of chains 18 together, and pass the hooked rods 10 over the hooks 13 and under the hooks 9, so as to be held on a tension. In order to produce a hay-rack from the closed condition of the top sides, chain 18 is unhooked at its middle, the rods 10 are disengaged, and the sides automatically fall in position at an angle to the sides of the main body, being prevented from falling too far by the automatic engagement of the hook on the end of each rod 10 with each of the hooks 13. When the sides have assumed this position, in order to strengthen them and enable them to support a heavy load the brace-rods 15 are placed in the apertures in the ends of sills 2, each rod resting upon the shoulder which it carries. The uprights 12 are next slipped into the loops 11, and the hay-rack is complete. My wagon-rack may be returned to the original position of the parts from any given position by simply reversing the steps taken in producing the said given position.

Having now described my invention, what I claim as new, and desire to secure by Letters Patent, is—

1. A wagon-rack comprising in its construction a main body, hooks carried by sides and

one end-gate of main body, hooks carried by top front end-gate, uprights carried by top front and rear end-gates, hooked rods, one of said hooked rods being carried by each of the top sides and connected thereto by means of ears, said hooked rods being adapted to engage said hooks carried by top front and under end-gates, substantially as described.

2. The main body comprising in its construction, a bottom supported by sills, the ends of said sills being beveled and apertured at an angle thereto, sides carrying hooks, braces connecting aforesaid sills with said sides, each of the braces extending over the beveled portion of each of the said sills and having an aperture which registers with the apertures in the sill, U-shaped pieces supporting said sills, and front and rear end-gates carrying pairs of loops, and hooks carried by said front end-gate substantially as described.

3. A wagon-rack comprising in its construction a main body having sills apertured at each end, ears carried by top sides, supporting rods carried by said ears and adapted to enter the apertures in said sills and rest upon a collar carried by each of said rods, eyes carried by the top sides for engaging the hooks carried by the sides and one end-gate of the main body, and means for holding top sides in a closed position by the connection of the hooked rods with the hooks on front of rack, substantially as described.

In testimony whereof I hereunto affix my signature in presence of two witnesses.

ALBERT L. SIPE.
